HEAT-TREATING OF GEAR TEETH

Francis S. Denneen, Cleveland, and William C. Dunn, Shaker Heights, Ohio, assignors to The Ohio Crankshaft Company, Cleveland, Ohio, a corporation of Ohio

Application March 23, 1942, Serial No. 435,912

4 Claims. (CL. 266—4)

This application is a continuation in part of our copending application Ser. No. 264,530, for Heat treating apparatus, filed March 28, 1939, and is concerned chiefly with the apparatus of Figs. 3 and 4 of that application and with modifications of that apparatus, all of which disclose means and method for heat treating the surface zones of gears and similar articles.

In the heat treatment of metals generally and in the hardening of ferrous metals in particular, there have been no teachings which would enable those skilled in the art to produce hardened zones of metal of predetermined characteristics as to depth and general contour on articles having abrupt or irregular changes in surface form by the use of electric heat. Surface hardening processes used heretofore were not adapted to the hardening of such surfaces as the contacting surfaces of gear teeth or splines, the side walls of sliding keys and keyways, the rifled interiors of gun bores, and many other similar surfaces. In the hardening of such surfaces as those above enumerated, it is often important that adjacent surfaces as well as the core or metal under the surface, be kept softer in order that it be sufficiently ductile to resist fractures due to shock, vibrations and other causes. For instance, in a gear tooth, the addendum surfaces should be hard in order to resist the abrasion of sliding and rolling contact of other tooth surfaces, while the metal in the dedendum and at the root of the tooth which does not contact with any wearing or abrasive element, but which is submitted to heavy bending stresses due to the cantilever construction of gear teeth, should remain strong and comparatively ductile to prevent breakage or the formation of incipient fractures. Experience has taught that brittleness in steel usually increases with hardness, and the greater the brittleness the more the metal is susceptible to the formation of surface cracks or incipient fractures which eventually extend far enough into the metal to cause complete failure of the section affected.

Our method and apparatus is applicable not only to gears, but to numerous other articles as hereinafter explained, such as splined shafts, reamers, drills, gun bores, the wearing surface of pulverizing and crushing machines, friction feed rolls and the like, and to almost any metal article requiring a hardened zone, particularly where there is an uneven surface.

With the aforementioned conditions in view, this invention then has as its chief object the provision of an apparatus and method whereby

the wearing surfaces of a gear may be hardened without detrimental changes affecting other parts of the gear. Another object is to provide a method and apparatus whereby the addendum portions of all teeth may be hardened simultaneously and uniformly. A further object is to provide a method whereby a portion of a gear after being hardened may be tempered to any desired degree. A still further object is to provide 5 a method and apparatus whereby internal teeth or splines may be hardened simultaneously with the hardening of external teeth on the same gears. Numerous other objects will become apparent from the following description in which 10 details of apparatus capable of producing improved results will be defined and new and advantageous steps in the procedure for obtaining 15 such results will be described or suggested to those skilled in the art of heat treating.

20 Fig. 1 is a longitudinal section of one form of our apparatus taken on line 1—1 of Fig. 2.

Fig. 2 is a fragmentary transverse section taken on line 2—2 of Fig. 1.

Fig. 3 is a fragmentary longitudinal section 25 of a further modification of our apparatus taken substantially on line 3—3 of Fig. 4.

Fig. 4 is a fragmentary section taken at 4—4 of Fig. 3.

Fig. 5 shows the moving and control mechanism employed with the apparatus of Figs. 1 and 2.

Fig. 6 is a view substantially as indicated at 6—6 of Fig. 5.

Fig. 7 is a view of the inductor as indicated 35 at 7—7 of Fig. 4.

Referring now to Figs. 1 and 2, we show one form of apparatus for accomplishing the results of our invention. In this apparatus the gear 35 is secured on an arbor 36 which is geared by gears 40 37 and 38 to the tube 39 onto which inductor bars are assembled. Locking means such as a spring actuated plunger 40 is provided for holding the gear in such position as to bring one of the inductor bars, as 40', into central position in the space between two adjacent teeth, as 41 and 42. With the inductor bar 40' in the position shown, high frequency current is caused to flow in this bar which induces currents of sufficient density in the adjacent surface zones of the teeth 41 and 43 to bring these zones to hardening temperature. Upon attaining this temperature, a quenching fluid is projected from the tube 39 through passages 43 in an insulating spider 44 and other passages 45 in the inductor bar, onto the heated surface of the teeth. A non-rotatable open side

tube 46 inserted in tube 39 prevents the quench from flowing into passages other than the ones leading to the heated tooth surfaces or to adjacent regions.

After one pair of tooth faces has thus been hardened, the gear 35 is rotated which, through the gearing above mentioned, rotates the group of inductor bars so as to bring the next bar, as 47 for instance, into the adjacent tooth space 48 in which position the group of inductors is locked by spring operated plunger 40 wedgingly engaging the space between two inductors until the hardening cycle for this position has been completed. By means of contacts made at the opposite ends of the inductor bar by brushes 50 and 51, when this bar is in heating position, the flow of current is restricted to that inductor bar much like the distribution of current in a commutator of a D. C. motor.

It will be evident that with a limited source of power and when the gear teeth are large, it may be possible to heat only one tooth face at a time instead of two opposite faces as above provided. To accomplish this the inductor may be so formed and positioned as to be brought into close proximity with one tooth surface only, it being spaced far enough from the surface of the opposite tooth to prevent injurious heating therein.

In the form of apparatus shown in Figs. 3 and 4 the gear 110, the teeth of which are to be hardened, is carried on bushing 111 which is brought into driving engagement with the end of shaft 112 by means of screw 113. Shaft 112 is rotatably supported in frame 114 of the apparatus and is rotated by gear 115 mounted thereon. A rotatable inductor is supported on and rotated with tubular shaft 117 which turns on stationary tube 118 to bring axial elements such as 119, 120 and 121 of the inductor into heating relation with the surfaces of successive teeth of gear 110. Gear 110 and the inductor are caused to rotate simultaneously and in correct relation with each other by gear 122 attached to tubular shaft 117 meshing with gear 115.

The inductor comprises a copper ring 125 to which a cylindrical group of axially extending inductor elements such as 119, 120 and 121 are securely attached. These elements are molded in insulating material such as 126 to form a rigid cylindrical assembly with the inductor elements projecting radially like the teeth of a gear and having their sides shaped to so conform with the faces of the teeth of gear 110 as to be brought into current inducing spaced relation with them. Current is delivered to the proper inductor elements from conductor rods 128 and 129 attached to a source of suitable inducing current. Two brushes located side by side and spaced to engage adjacent inductor elements as shown at 130 and 130'. These brushes are held in engagement with the radial disc-like surface comprising the ends of the inductor elements and the insulation 126 interposed between these elements and carry the current from the conductor rods to the inductor elements, springs such as 131 holding the brushes in contact with the ends of the inductors. The brushes are thus brought into current conducting engagement with the ends of the elements so that current flows from rod 128 thru one element such as 120 then across thru ring 125 to an adjacent element such as 121 and then back to rod 129 which is shown in Fig. 7. There being no contact with any other element such as 119 no current will flow in such other element until the inductor is turned. It will be observed that current flows

in opposite directions in elements 120 and 121 to heat the sides of tooth 135. When the inductor and gear 110 are rotated an amount corresponding to one tooth space, elements 119 and 120 will move into current conducting contact with brushes 130 and 130' corresponding to the positions formerly occupied by elements 120 and 121 respectively and tooth 136 will enter the space between them corresponding to that occupied by tooth 135.

In this form of the apparatus the gears are indexed by a pawl and ratchet mechanism similar to that shown in Figs. 5 and 6 hereinafter described. Shaft 138 is motor driven at a sufficiently slow speed to provide proper timing. Cam 139 operates pawl 140 to rotate ratchet disc 141 which turns shaft 117 to move the inductor one gear space at a time. The heating and quenching are timed by drum or other timing device such as 142. Relay 143 operates the heating current connecting switch 144 and relay 145 operates the quenching fluid supply valve 147.

Quenching fluid is delivered thru tubular shaft 118 which has a port 149 so located as to deliver the quenching fluid thru only passages such as 150 and 151 which lead immediately adjacent to as shown or thru only the inductor elements such as 120 and 121 which are in heating positions relative to the gear tooth such as 135. Passages such as 152 in tubular shaft 117 serve with port 149 as a distributor to limit the flow of quenching fluid to the correct inductor element passages.

It will be obvious that the apparatus above described comprises inductor members which automatically are brought into heating relation with surfaces of gear teeth as the gear is progressively rotated or indexed by steps, usually one tooth at a time. However, by multiplying the number of inductors and properly forming them several teeth can be hardened at each indexed location.

Figs. 5 and 6 show a diagram of the electrical connections and related means for controlling timed heating and quenching when the apparatus similar to that of Figs. 1 and 2 is employed. In this timer, discs 160 and 161 are carried by shaft 162 which shaft is driven by coupling 163.

Pawl comprising members 164 and 164' carried by an eccentric or cam 165 advances gear 38 one or more teeth at a time to rotate gear 35 the correct amount to bring an inductor member such as 45 into correct relation with two teeth of this gear. A brush contact 166 on disc 160 usually by a relay controls switch 167 in the circuit supplying current to terminals 168 and 169 of the inductor unit and brush contact 170 controls valve 171 for delivering fluid to tubular shaft 46 for quenching the teeth of the gear.

Other forms may be employed embodying the features of our invention instead of the one herein explained, change being made as regards the means and the steps herein disclosed, provided the elements stated by any of the following claims or the equivalent of such stated elements be employed, whether produced by our preferred method or by others embodying steps equivalent to those stated in the following claims.

We therefore particularly point out and distinctly claim as our invention:

1. In apparatus of the class described for heat treating teeth of a gear, means for supporting the gear to rotate on an axis, an axially supported rotatable inductor of generally cylindrical form, said inductor comprising a plurality of conductor bars, the said bars lying generally along

elements of the cylinder and projecting substantially radially from the cylinder in spaced relation substantially like teeth of the gear, insulating means separating the bars from each other along elements of the cylinder, gearing connecting the inductor and the gear supporting means to rotate the inductor in timed relation with the gear and to bring successive inductor bars into successive tooth spaces of the gear, the said bars being adapted to enter said tooth spaces in closely spaced relation with faces of the teeth of the gear, and means for supplying inducing current to the bars when the bars have entered corresponding tooth spaces to induce heating current in faces of teeth adjacent to the bars.

2. In apparatus of the class described for heat treating teeth of a gear, means for supporting the gear to rotate on an axis, an axially supported rotatable inductor of generally hollow cylindrical form, a cylindrical wall of said inductor comprising a plurality of conductor bars, the said bars lying generally along elements of the cylinder and projecting substantially radially from the cylinder in spaced relation substantially like the teeth of the gear, insulating means separating the bars from each other along elements of the cylinder, gearing connecting the inductor and the gear supporting means to rotate the inductor in timed relation with the gear to bring successive inductor bars into successive tooth spaces of the gear, the said bars being adapted to enter said tooth spaces in closely spaced relation with faces of the teeth of the gear, means for supplying inducing current to the bars when the bars have entered corresponding tooth spaces to induce heating current in surface zones of the tooth faces, fluid delivery passages through the cylindrical wall of the inductor, and means associated with the axial support of the inductor for delivering fluid to the fluid delivery passages of the inductor to cool the inductor bars and to quench the surface zones of the gear teeth; said last named means comprising the substantially fixed tubular shaft axially supporting the inductor, the tubular shaft having a port through a wall thereof, said port being disposed to register with successive fluid delivery passages through the wall of the inductor to selectively deliver the fluid to those passages through the inductor wall which lie adjacent to the tooth of the gear being heated, a part of the wall of the tubular shaft serving to exclude fluid from other passages through the inductor wall to confine quenching to those parts of the gear which it is desired to quench.

3. In apparatus of the class described for heat treating teeth of a gear, means for supporting the gear to rotate on an axis, a rotatable inductor axially supported on a tubular shaft, the inductor comprising an insulating hollow cylindrical wall, a plurality of inductor bars, said bars being supported by said cylindrical wall and projecting substantially radially therefrom in

spaced relation substantially like the teeth of the gear, gearing connecting the inductor and the gear supporting means to rotate the inductor in timed relation with the gear to bring successive inductor bars into successive tooth spaces of the gear, the bars being adapted to enter the tooth spaces in closely spaced relation with faces of the teeth of the gear, means for supplying inducing current to the bars when the bars have entered corresponding tooth spaces to induce heating current in surface zones of the tooth faces, fluid delivery passages through the cylindrical wall of the inductor, and means associated with the axial support of the inductor for delivering fluid to the fluid delivery passages of the inductor to cool the inductor bars and to quench the surface zones of the gear teeth; said last named means comprising the substantially fixed tubular shaft axially supporting the inductor, the tubular shaft having a port through a wall thereof, said port being disposed to register with successive fluid delivery passages through the wall of the inductor to selectively deliver the fluid to those passages through the inductor wall which lie adjacent to the tooth of the gear being heated, a part of the wall of the tubular shaft serving to exclude fluid from other passages through the inductor wall to confine quenching to those parts of the gear which it is desired to quench.

4. In apparatus of the class described for heat treating spaced projections on a substantially cylindrical article, means for supporting the article to rotate on an axis, a rotatable heater axially supported to rotate on a substantially fixed tubular shaft, the heater comprising a plurality of heating members, the said members having parts projecting from the heater in spaced relation substantially like teeth of a gear, gearing connecting the heater and the article supporting means to rotate the heater in timed relation with the article to bring successive heater members into heating proximity with successive projections to heat surface zones of the projections, fluid delivery passages through a part of the heater, and means associated with the axial support of the heater for delivering fluid to the fluid delivery passages of the heater to cool parts of the heater and to quench the surface zones of the projections, said last named means comprising a substantially fixed tubular shaft axially supporting the heater, the tubular shaft having a port through a wall thereof, said port being disposed to register with successive fluid delivery passages through the heater to selectively deliver the fluid to those passages through the heater which lie adjacent to the projection being heated, a part of the wall of the tubular shaft being adapted to serve to exclude fluid from other passages through the heater to confine quenching to those parts of the article which it is desired to cool.
